DESIGN FOR A PANEL BOARD

Walter D. Teague, New York, N. Y., assignor to
Square D Company, Detroit, Mich., a corpora-
tion of Michigan

Application November 8, 1933, Serial No. 49,677

Term of patent 14 years

To all whom it may concern:

Be it known that I, Walter D. Teague, a citizen of the United States of America, residing at New York city, in the county of New York, in the State of New York, have invented a certain new, original, and ornamental Design for Panel Board, of which the following is a specification, reference being had therein to the accompanying drawing, forming a part thereof, wherein;

Figure 1 is a front elevation of a panel board structure;

Figure 2 is a bottom plan view of the construction illustrated in Figure 1;

Figure 3 is a side elevation of the construction illustrated in Figure 1;

Figures 4, 5 and 6 respectively are surface sections taken on the lines 4—4, 5—5 and 6—6, respectively, of Figure 1.

I claim:

The ornamental design for a panel board substantially as shown and described.

WALTER D. TEAGUE.
